Des. 211,124
Patented May 21, 1968

211,124

PRESSING IRON SUPPORT

Jack P. Echols, Dallas, Tex.
(107 S. Interurban, Richardson, Tex. 75080)

Filed Sept. 18, 1967, Ser. No. 8,645

Term of patent 14 years

(Cl. D49—6)

Fig. I

Fig. II

Fig. III

FIG. I is a perspective view of pressing iron support showing my new design;

FIG. II is a side elevational view of same;

FIG. III is a bottom plan view.

I claim:

The ornamental design for a pressing iron support, substantially as shown.
